CLAIM

The ornamental the design for a ringed compressed coaxial cable F-connector, as shown and described.

DESCRIPTION

FIG. 1 is an isometric view of a ringed compressed coaxial cable F-connector showing my new design;

FIG. 2 is a side view thereof; the opposite side and the left and right elevation views comprise mirror images thereto;

FIG. 3 is a front end view of thereof; and,

FIG. 4 is a rear end view thereof.

The internal features shown in dot-dot-dash broken lines appearing in the front and rear end views of FIGS. 3 and 4, respectively, represent unclaimed subject matter and form no part of the claimed design.
